Alfred D. Madwell

Inventor.

David Young.

By Joshua B. Webster Atty.

UNITED STATES PATENT OFFICE.

DAVID YOUNG, OF STOCKTON, CALIFORNIA.

TRAVELING THRASHER.

SPECIFICATION forming part of Letters Patent No. 326,617, dated September 22, 1885.

Application filed February 11, 1885. (No model.)

To all whom it may concern:

Be it known that I, DAVID YOUNG, a citizen of the United States, residing at Stockton, in the county of San Joaquin and State of California, have invented certain new and useful Improvements in Traveling Thrashers, of which the following is a specification, reference being had therein to the accompanying drawings.

My invention relates to an improvement in traveling thrashers; and it consists in a frame of a peculiar construction supported by suitable driving-wheels, and having operating devices arranged and located in a novel manner, all as hereinafter described and claimed.

The purpose of this invention is to improve the construction of the traveling thrasher for which Letters Patent No. 311,705 were granted to me February 3, 1885, so as to make it more convenient in use and more effective in operation. I rearrange the operating-gearing and dispense with the gear-wheels *e*, *f*, *g*, *i*, and *j*, as shown in said Letters Patent, and in their place substitute belts and pulleys. The advantage of such change and substitution is that the machine is of simpler construction and of lighter draft and more durable, because the parts are fewer, simpler, cheaper, and more easily renewed. The machine also is operated more easily with belting than with gearing.

In the accompanying drawings, Figure 1 is a plan view of that part of a traveling thrasher which shows my invention. Fig. 2 is a view of the right side of the same.

The frame of my machine, upon which the thrasher and operating devices are supported, consists of the main cross-beams *C* and *C'*, rear and front, respectively, extending the entire width of the machine, and the longitudinal beams *A*, *B*, *B'*, and *A'*. All of the longitudinal beams are bolted or otherwise secured to cross-beams *C* and *C'*. The beams *B* and *B'* extend forwardly of beam *C* and are secured to girder *C'*, to which is secured the axle of front supporting-trucks. A supporting and driving wheel, *D*, has its journal-bearings secured to beams *A* and *B*. From this wheel the motion necessary to actuate the different portions of the thrasher, &c., is derived by means of suitable gearing, as will be shown. A supporting-wheel, *E*, has its journal-bearings secured to beams *B'* and *A'*.

b represents the shaft of the wheel *D*, having its journal-bearings secured, as shown, to beams *A* and *B*. To the inner end of shaft *b* is fixed a large spur-wheel, *a*. A shaft, *d*, which has its bearings upon beams *B* and *B'*, at a suit-

able distance to the rear of shaft *b*, has fixed to it the pinion *c*, which meshes with spur-wheel *a*. The other end of shaft *d* has fixed to it a large spur-wheel, *e*. A shaft, *g*, which has its bearings upon beams *B* and *B'*, at a suitable distance to the rear of shaft *d*, has fixed to it a pinion, *f*, which meshes with spur-wheel *e*. A pulley, *h*, is fixed to left-hand end of shaft *g*. The pulley *h* is connected by a belt with the system of pulleys and shafts operating the works of the separator and thrasher, except the cylinder and fan-mill and feeder, which are operated by a pulley, *i*, at the right-hand end of the shaft *g*, which is connected by belt *j* with a pulley, *k*, on the right-hand end of the cylinder-shaft *l*. Pulley *n* on the left-hand end of the shaft *l* may be connected by belt with pulley *O* on end of shaft *P*, actuating a self-feeder in front of the cylinder, while a pulley, *m*, or the left-hand end, outside of pulley *n* of shaft *l*, can operate the fan-mill by a connecting-belt.

The thrasher and separator, &c., may be of any ordinary or approved construction, and the parts not herein shown or described may be belted or geared as required, motion being received primarily from the wheel *D* and the system of shafts and gearing herein described.

What I claim as new and of my invention is—

1. As an improvement in traveling thrashers, the combination, with a supporting-frame, of a drive-wheel, a large gear-wheel on the shaft thereof, a transverse shaft mounted in rear of the drive-wheel, and carrying at one end a pinion intermeshing with the said gear and at the other end a large gear-wheel, a shaft with a pinion intermeshing with the gear-wheel on the transverse shaft and carrying a band-pulley, the cylinder-shaft journaled in the forward end of the machine and carrying a pulley, and a connecting-belt, the whole operating substantially as and for the purpose specified.

2. The combination of the frame, the drive-wheel *D*, gear-wheel *a* on its shaft, the shaft *d*, mounted forward of the drive-wheel and carrying pinion *c*, and gear-wheel *e*, the shaft *g*, with pinion *f*, and band-pulleys *h* *i*, and shaft *l*, cylinder mounted forward of the drive-wheel and provided with pulleys *k* *m* *n*, combined to operate substantially as and for the purpose specified.

In testimony whereof I affix my signature in presence of two witnesses.

DAVID YOUNG.
